UNITED STATES PATENT OFFICE.

ABE P. DUNMAR, OF COLUMBUS, OHIO, ASSIGNOR TO LOUIS STETELMAN, OF COLUMBUS, OHIO.

BOOK-SUPPORT.

1,245,890.

Specification of Letters Patent.

Patented Nov. 6, 1917.

Application filed September 28, 1914. Serial No. 863,979.

To all whom it may concern:

Be it known that I, ABE P. DUNMAR, a citizen of the United States, residing at Columbus, in the county of Franklin and State of Ohio, have invented certain new and useful Improvements in Book-Supports, of which the following is a specification.

My invention relates to book supports of the type that may be readily transported and used conveniently in properly supporting an open book at the proper angle of inclination for ease and comfort in reading. Such books as those of considerable weight and also those of comparative newness are 10 bothersome and bunglesome to handle and it is to this end that a structure is contemplated by which the book may be conveniently and effectively supported.

One of the main objects of my invention resides in the provision of a structure whereby the book may be supported in an open position and the exposed leaves on opposite sides of this open book be firmly held in position against possible turning. 20 In this connection, I have made my leaf engaging structure adjustable to accommodate various thicknesses of books and of such construction that it may be readily thrown out of engagement to facilitate 25 turning of the leaves.

Other objects of my invention will become more apparent after a further detailed description of the accompanying sheet of drawings, in which similar characters of reference designate corresponding parts, and in which:

Figure 1 is a side elevation of my assembled book support;

Fig. 2 is a view in perspective of the leaf holding structure;

Fig. 3 is a fragmentary view in perspective showing a detail of construction;

Fig. 4 is a fragmentary top plan view showing the means for supporting one side 45 of the book;

Fig. 5 is a section taken on line 5—5 of Fig. 4, and;

Fig. 6 is a plan view of the lower portion of the foot support.

50 In the drawings, the book supporting table is shown at 1, this table being provided along its lower edge with an upstand-

ing ledge 2 against which it is intended the cover portions of the book may rest. The lower edge of this table is provided with a plurality of feet such as shown at 3, the lower portions being rounded as at 4 for a reason that will appear later. The upper half of the underside of the table is also provided, preferably centrally, with a rod 5, this rod being preferably of flattened U-shaped construction. In order that the table itself may be mounted to assume various positions of inclination, the rear foot 6 has been made somewhat greater in length than that shown at 3 and is also provided with laterally projecting rounded portions 7. The upper end of this foot is provided with a hole 8 through which the rod 5 is arranged to pass, the edges of this hole being so spaced and constructed that they form a frictional grip upon the rod. In order that the foot will not be readily dislodged when the table structure is moved from one position to another, or is slightly elevated, I have provided a projection 9 adjacent the under portion of the metal surrounding the hole 8, this projection 9 being so located that a slight tilting action of the rod 6 will cause it to come into engagement with the rod 5 itself. Because of the various degrees of inclination that the table may assume when it is properly set, I have rounded the various feet as has been described and shown at 4 and 7.

When a book is placed upon the table and opened either near its beginning or its end, it is desirable that the two exposed leaves be in substantially the same plane and to this end I have provided a supporting structure in the form of a member having a T-shaped head 10 and a depending shank portion 11, slidable through a suitable aperture 12 in the body of the table 1. This supporting element may be positively held in any adjusted position by means of the thumb screw shown at 13. In order that this supporting member will not interrupt the plane upper surface of the table when in its lowermost position, I have notched out a small portion thereof as is shown at 14, the supporting member itself being shown dotted in its lowermost position in Fig. 5. Each side portion of the

table 1 is usually provided with an aperture such as that indicated at 12 and if desired, a separate supporting member may be provided for each aperture. If this is not desired, a single supporting member may be provided and this member used interchangeably between the several apertures.

When a comparatively large book is supported upon the table, the outside lowermost corners of the leaves tend to draw downwardly because the edges of the leaves themselves cannot engage the ledge 2 for the reason that it is customary in binding books to make the cover slightly larger than the leaves themselves. In order to prevent this sagging and, therefore, to save the binding, I have provided the lower edge of the table 1 with a number of members such as are shown at 15. Each of these members is pivoted, preferably adjacent the corner, to the table 1 by means of the attaching screw shown at 16. The free end of each of the members 15 is given an inward bend 17 and is then again bent at right angles as at 18, the distance the portion 17 overlaps the ledge 2 being approximately one-eighth inch or the amount that the book cover usually overlies the leaf structure. If the device is intended to be used with a small book, these last described members 15 may be swung about their pivotal connections to assume a lowered position as is illustrated in dotted lines in Fig. 3.

The structure used for maintaining the exposed leaves of an open book in flat position is best shown in Fig. 2. This structure comprises a member 19 designed to be fixedly secured to the upstanding ledge 2 of the table 1 by screws or bolts, this fitting 20 being provided with an opening 20 of a size to slidably receive a standard 21. This standard 21 is also provided with a lateral projection 22 terminating in a finger grip 23 arranged to coöperate, by means of a coiled spring 24, with a similar finger grip 25 rigidly carried by a toothed member such as is shown at 26. This toothed member is pivotally attached at 27 to the lateral projection 22 of the standard 21 and its teeth 28 are so arranged that they coöperate with similar teeth formed upon the projection 29 on the fitting 19. The leaf engaging structure proper comprises a T-shaped engaging member 30 pivoted to the upper end of the standard 21 at 31. It will be noted, by reference to Figs. 1 and 2, that this pivot point is located a slight distance below the upper end of the standard itself and in fact, is located a distance below this end sufficient to accommodate the square end portion of a locking finger 32 pivoted at 33 to the engaging member 30. This locking finger is preferably right angular in shape, its upstanding leg being formed to assume the proportions of a finger grip 34.

The operation of this leaf engaging structure is as follows: It is assumed that a book is lying in open position upon the table 1, whereupon the finger grips 23 and 25 are forced toward each other against the pressure of the spring 24. This action causes an outward movement of the toothed member 26 and when its tooth 28 comes out of engagement with the tooth on the projection 29, it is possible to move the standard 75 21 up or down to the desired position. The T-shaped leaf engager 30 is made to lie in engagement with the top of the open book and the standard 21 is then moved downward until this engager 30 assumes the 80 right angular position as is shown in full lines in Fig. 1 and as is also shown in Fig. 2. Further movement downwardly of the standard 21 will, therefore, be impossible because upward movement of the member 85 30 is precluded by the engagement of the square end of the locking finger 32 with the upper inside edge portion of the standard 21. Should it be desired to turn to the next page, the finger grip 34 on the locking finger 90 95 is pressed in the direction of the book, thereby releasing the engagement of the finger 32 with the upper end of the standard. This release then permits upward swinging of the member 30 about its pivot 31, one upward position of both the member 30 and the locking finger being shown in dash lines in Fig. 1. After the page has been turned, the leaf engager may again be locked in position by a reversal of the operations just 100 outlined.

What I claim, is:

1. A book support comprising a table member for supporting a book in open position, a member having an opening therethrough and toothed on one side carried by the lower edge of said table member, a standard slidably up and down in the opening in said toothed member, a complementary toothed member carried by said standard in 105 coactive relation with said first named toothed member, means for holding said complementary toothed member in engagement with said first-named toothed member to hold said standard in any adjusted position, and means carried by the upper end of said standard to engage the book leaves of an open book to maintain them in position.

2. A book support comprising a table member for supporting a book in open position, a member having an opening therethrough and toothed on one side carried by the lower edge of said table member, a standard slidably up and down in the opening in said toothed member, a complementary 110 toothed member pivoted to said standard at its upper end, a spring acting between said standard and said complementary toothed member to hold the teeth on said two toothed members in engagement, a T-shaped leaf 115 120 125 130

holder pivoted to the upper end of said standard, and a square ended right angular locking finger pivoted to said holder, the square end portion being arranged to engage said standard to prevent upward movement of said holder when in engaging position.

In testimony whereof I affix my signature in presence of two witnesses.

ABE P. DUNMAR.
